JOHN H. URSPRUNG AND JOSEPH B. URSPRUNG, OF PHILADELPHIA, PENNSYLVANIA, ASSIGNORS OF ONE-HALF TO JOHN A. HUNTER AND MARY A. HUNTER, OF PHILADELPHIA, PENNSYLVANIA.

THREAD-CONTROLLING MECHANISM FOR SEWING-MACHINES.

No. 804,508.

Specification of Letters Patent.

Patented Nov. 14, 1905.

Application filed August 18, 1904. Serial No. 221,182.

To all whom it may concern:

Be it known that we, JOHN H. URSPRUNG and JOSEPH B. URSPRUNG, citizens of the United States, residing in the city of Philadelphia, 5 State of Pennsylvania, have jointly invented certain new and useful Improvements in Thread-Controlling Mechanism for Sewing-Machines, of which the following is a full, clear, and exact description, reference being 10 had to the accompanying drawings, forming a part of this specification.

Our invention relates to sewing-machines wherein it is essential or desirable to so operate the tension device for the lower thread that the 15 exact length of thread drawn forward necessary to form a stitch may be positively regulated and controlled and the tightening of such stitch be effected by a positive braking of the tension-drum at suitable intervals and during 20 the formation of such stitch and after the length of thread necessary to make the same has been let off the tension-drum by the corresponding alternate release of the brake mechanism.

25 In sewing-machines designed for boot and shoe sewing, wherein a waxed thread is employed, it is desirable, if not essential, to produce a perfect product that no more thread than is necessary to form the stitch should be 30 let off and that the stitch should be drawn tight.

Our invention is especially advantageous 35 to produce both those results, as our brake device operates to positively restrain rotation of the tensioned thread-drum at each stitch-forming interval, hence operating to draw tight the previously-formed stitch.

Our present invention consists in supplying 40 such a positive let-off and brake device in mechanical and functional coaction with a thread-drum controlled, primarily, by a tension device, the brake device and the tension device controlling the rotation of the drum alternately, the interval of time between the 45 alternate action of each being governed by cam mechanism of the sewing-machine acting in unison of time with the stitch-forming devices thereof.

In the drawings illustrating our invention, 50 Figure 1 is a front elevation of the device in its best form. Fig. 2 is a like view of the supporting-frame, the brake-lever with its brake-shoe, the shaft in the frame, the rota-

table thread-drum mounted thereon, and the tension device for the same. Fig. 3 is an end 5 view of the device shown in Fig. 1, and Fig. 4 is a like view from the opposite end of the same device.

We need not describe in detail a lock-stitch boot or shoe sewing machine nor its positively- 60 acting cam devices to actuate the hereinafter-described brake-controlled tension-drum, it being sufficient to refer to Letters Patent No. 715,323 granted to us, dated December 9, 1902, wherein such a sewing-machine with which 65 our present invention is adapted to operate is therein fully set forth.

Referring now to the accompanying drawings, 1 indicates a suitable framework constituting part of the frame of the sewing-machine and in proximity to the main cam-wheel 70 of the machine, such as the cam-wheel 3, carrying cams 4 and 5. (Shown in Fig. 2 of the drawings of our said Patent No. 715,323.) A supporting-plate 2 is screwed fast to said 75 framework 1, and upon said plate is a stud 2^x, upon which is rotatably mounted the tension-drum 65, which is therefore free to rotate on said stud under the yieldingly restraining influence of the tension mechanism, save when 80 positively held from rotation by the action of the brake mechanism. The tension-drum 65 is provided with an annular groove 65^a for the passage of the thread and a bearing-surface on which the friction-shoes 68 of the 85 brake-levers 66 and 67 impinge. (See Figs. 3 and 4.) On the end of the stud 2^x which projects beyond the face of the drum 65 and bearing against the same is a collar 6, serving as a bearing for a spiral spring 7, and on the end 90 of the stud and bearing against the spring is a thumb-nut 8, said elements 6, 7, and 8 constituting the tension device, the mode of operation of which in creating the desired tension is obvious. The needle-thread is drawn 95 from a spool suitably located on the frame of the sewing-machine and passes around the drum 65 in the groove 65^a thereof, being led and directed thereto by the guide-wheel 9 (see Fig. 4) and being held on the latter by a cover-hook 10. The relative position of the guide-wheel to the thread-drum is best seen in the side elevation in Fig. 1. This guide-wheel is mounted rotatably on the lower end of the arm 71, which carries on its other end a friction-roller 72, which is disposed in the path 100 105

of actuating-cams, such as cams 4 and 5 on the periphery of a cam-wheel, such as cam-wheel 3, (shown and described in our aforesaid Patent No. 715,323,) or other suitable actuating devices. The adjustment of position of the guide-wheel 9 relatively to the thread-drum 65 is effected as follows: The said guide-wheel is rotatably mounted by means of the centrally-disposed set-screw on the lower end 5 of the arm 71, which is centrally slotted and slides longitudinally between the spaced parts of the bracket 74, a set-screw passing through the slot in the arm 71, holding the spaced parts of the bracket-arm 74 together. (See 10 Fig. 1.) The lower portion of the arm 71, whereon the guide-wheel 9 is mounted, projects below the bracket-arm 74, and the sliding movement referred to is effected, as seen in Fig. 4, by means of the set-screw 75. In 15 said Fig. 4, which is an end view, the guide-wheel 9 will be seen mounted by its shaft on the lower end of the adjustable arm 71 above the lower end of the bracket 74, in which said arm 71 is adjustable longitudinally by means 20 of the set-screw 75, which has its bearing in said lower end of the bracket. As is obvious from Fig. 4, a forward turn of the set-screw in its bearing (which is fixed relatively to the arm 71) will effect a longitudinal adjustment 25 of the arm 71 in its bracket-bearing 74, thereby altering the position not only of the friction-roller 72, but of the thread-guide wheel 9, relatively to the tension-drum 65 and relatively to the brake mechanism governing the 30 drum.

The bracket-frame 74 (carrying the arm 71 with its friction-roller 72 and guide-wheel 9) is mounted pivotally on the supporting-frame 2, preferably and as shown in the drawing 40 Fig. 1, by means of a lever 70, mounted to rock on the stud 2^x between the face of the frame 2 and the inner face of the thread-drum 65. That method and means of pivotally mounting the arm 71 enables us to employ the 45 rocking lever 70 for the additional purpose of actuating the brake-levers 66 and 67, though we do not limit ourselves to that precise mechanism for performing that function.

The brake mechanism consists of the lever 50 66 and the lever 67, or either of them singly. Each carries a friction-shoe 68. We prefer to use a double brake, for the reason that when one such lever only is employed the braking is effected by causing the drum 65 to 55 bind on the stud 2^x, while by using both the rotation of the drum is prevented by a biting action between the two oppositely-disposed brake-levers and without pressing the drum against its supporting-stud. Each of these 60 brake-levers 66 and 67 is hung by a pivot-pin 66^a and 67^a to the supporting-frame 2 at diagonally opposite corners. Each brake-lever 66 and 67 is connected to the rocking lever 70 by a link connection 69. In this preferred 65 form of our invention the link connection

joining the free ends of either or both of the brake-levers 66 and 67 to the rocking lever 70 being on the fulcrum side of the latter and the brake-levers being also likewise suitably disposed, a rocking movement of the lever 70 through the actuating-arm 71 will tend to draw the friction-shoes of the brake-levers against the periphery of the thread-drum 65 and positively arrest its revolubility, while movement of said parts in the opposite direction will release the brake and allow the drum to rotate under the yielding restraint of the tension-spring only. In order to insure a quick and positive release motion of the brake-lever, we prefer to add a spring 10, (see Fig. 80 1,) one end of which is fixed at the fixedly-pivoted end of the brake-lever and the other end is passed under a projection 11 on the free or linked end thereof.

We desire it understood that we do not confine ourselves to the specific mechanism shown and described, as many of the adjunctive elements may be varied or even omitted. We have shown separately in Fig. 2 (read in connection with Figs. 3 and 4) the features which 90 are absolutely essential to any embodiment of our invention, these being the supporting-frame 2, the stud 2^x, the thread-drum axially and rotatably mounted thereon, the tension device yieldingly governing the rotation of 95 the drum under the pull of the thread, and the brake-lever 66, carrying friction-shoe 68 and pivotally mounted at one end on the supporting-frame which carries the thread-drum in such manner that it may be vibrated in 100 both directions by appropriate means actuating its free end and its friction-shoe be thereby brought into and out of contact with the periphery of the thread-drum normally controlled by the tension device.

Having thus described our invention, what we claim as new, and desire to secure by Letters Patent, is—

1. The combination in a sewing-machine of a peripherally-grooved thread-drum about which the thread is passed, a supporting-frame carrying a stud on which said drum is axially and rotatably mounted, tension devices mounted on said stud operating to limit the free rotation of the drum, a braking mechanism 110 adapted to positively restrain its rotation at each stitch-forming interval, consisting of a brake-lever carrying a brake-shoe and pivotally mounted by one of its ends on said supporting-frame and over the periphery of the drum, and means to vibrate the brake-lever in both directions, consisting of a rocking lever pivoted axially of the drum with connecting actuating means between it and the brake-lever.

2. The combination, in a sewing-machine, of a thread-drum about which the thread is passed, a supporting-frame upon which said drum is axially and rotatably mounted, tension mechanism normally acting on the drum, 130

a rocking lever pivoted axially of the drum, a brake-lever carrying a friction-shoe and pivotally mounted by one of its ends on said supporting-frame, over the periphery of the 5 drum, and a link connecting the free end of the brake-lever with one end of the rocking lever.

3. The combination, in a sewing-machine, of a supporting-frame carrying a stud, a tension-controlled thread-drum axially and rotatably mounted on said stud, a brake-lever carrying a friction-shoe and pivotally mounted by one end on the supporting-frame and over the periphery of the drum, means to 10 vibrate the free end of the brake-lever at predetermined times, a guide-wheel about which the thread is passed on its passage to the thread-drum, and means to adjustably support said guide-wheel in front of the thread-drum and to automatically raise and lower it 15 as the brake-lever is vibrated to brake or release the thread-drum.

4. The combination in a sewing-machine,

of a supporting-frame carrying a stud, a rocking lever axially mounted on said stud, a 25 thread-drum rotatably mounted thereon, a tension device on the end of the stud normally governing the free rotation of the drum, a brake-lever carrying a friction-shoe, and pivotally mounted by one end to said supporting-frame, link connection between the free end 30 of the brake-lever and one end of the rocking lever, a bracket fixedly secured to one end of the rocking lever, an arm adjustably mounted in said bracket and carrying at one end a 35 friction-roller and at the other end a guide-wheel arranged in the path of the thread as it is let off to the thread-drum.

In testimony whereof we have hereunto affixed our signatures this 16th day of April, 40 A. D. 1904.
